Primary Examiner — Cynthia Ramirez*Assistant Examiner* — Xavier Marti-Santos(74) *Attorney, Agent, or Firm* — Miles & Stockbridge P.C.; David R. Schaffer(57) **CLAIM**

The ornamental design for a sofa, as shown and described.

DESCRIPTION

FIG. 1 is a left front perspective view of a sofa showing my new design;

FIG. 2 is a right rear perspective view thereof;

FIG. 3 is a left front perspective view, shown in the reclined position thereof;

FIG. 4 is a front elevational view, shown in the non-reclined position thereof;

FIG. 5 is a left elevational view thereof, the right side elevation being a mirror image;

FIG. 6 is a right rear perspective view, shown in the reclined position thereof; and,

FIG. 7 is a top plan view, shown in the non-reclined position thereof.

The broken lines in the figures are for the purpose of illustrating portions of the sofa, which form no part of the claimed design.
